US00D532212S

(12) **United States Design Patent** (10) **Patent No.:** **US D532,212 S**
Bell (45) **Date of Patent:** **** Nov. 21, 2006**

(54) **CHAIR**

(75) Inventor: **Ted Allen Bell**, Killen, AL (US)

(73) Assignee: **Suncoast Aluminum Furniture, Inc.**,
Ft. Myers, FL (US)

(**) Term: **14 Years**

(21) Appl. No.: **29/234,380**

(22) Filed: **Jul. 18, 2005**

(51) **LOC (8) Cl. 06-01**

(52) **U.S. Cl. D6/376; D6/369; D6/379**

(58) **Field of Classification Search** D6/334-336,
D6/358, 365, 369, 374, 376, 379, 380, 500,
D6/501, 502; 297/445.1, 446.1, 452.63, 452.64
See application file for complete search history.

(57) **CLAIM**

The ornamental design of a chair, as shown and described.

DESCRIPTION

FIG. 1 is a right perspective view of the chair showing my
new design; and,

FIG. 2 is a left perspective view of the design shown in FIG.
1.

The rear of the decorative open pattern portion of the
backrest is identical to the front of that portion. Likewise, the
bottom of the braided pattern of the seat portion is identical
to the top of that portion.

1 Claim, 2 Drawing Sheets
